UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

VALVE FOR ROCK DRILLS.

Application filed October 24, 1923. Serial No. 670,396.

To all whom it may concern:

Be it known that I, FRED M. SLATER, a citizen of the United States, and a resident of Easton, county of Northampton, and State of Pennsylvania, have invented a certain Valve for Rock Drills, of which the following is a specification, accompanied by drawings.

This invention relates to fluid actuated rock drills, but more particularly to a fluid actuated valve of the spool type, controlling the inlet supply, a free exhaust being controlled by the piston.

The objects of the present invention are to obtain an inlet valve which is quick and positive in action, delicately balanced, and effectively controlled by the live air and by the exhaust from the main cylinder.

Other objects of the invention are to produce a valve of the type referred to, which will start the hammer piston in operation regardless of the position in which the rock drill is held, and will continue to function automatically under substantially all conditions, thus keeping the piston in continuous operation.

Further objects of the invention are to prevent the valve from centering or stopping at times, which is a serious disadvantage if such stoppage occurs, and on the other hand, if the piston tends to stop or actually comes to rest in the length of the cylinder for any reason, this improved valve will automatically become unbalanced owing to the construction of the ports and passages and will be thrown in a direction to immediately start the piston in operation again.

Valves of this type, or in fact of any type operating in conjunction with a free exhaust from the cylinder, should not pass more air than can be easily taken care of by the exhaust, nor should they pass too little air, so that the valve travel should be either too great nor too small, and the valve should be properly timed to produce the requisite number of hammer blows per minute of requisite strength and efficiency, as otherwise the drilling will be reduced.

Although for simplicity of illustration, the valve is shown applied to a "hand held" drill, this valve is especially suitable for a stope drill of the hammer type, having rifle bar rotation, and a fluid pressure feeding element, such as an air feed cylinder. A rifle

bar stoper having air feed, throws extra work upon the hammer piston, owing to the continued pressure of the feeding element, and the valve must function positively, evenly and continuously without stopping, in order to keep the rotating hammer in full operation and striking powerful blows under the most severe conditions.

The invention is illustrated in one of its preferred forms in the accompanying drawings, in which—

Figure 1 is a longitudinal sectional elevation of a fluid actuated rock drill having the improved valve applied thereto,

Figure 2 is a detail longitudinal sectional elevation of a portion of the machine showing the valve in a different position from that indicated in Figure 1, and

Figure 3 is an enlarged detail longitudinal sectional view taken through the valve and valve chest.

Referring to the drawings, the rock drill to which my valve is applied, for purposes of illustration, comprises a cylinder A having a reciprocating piston B provided with a head C and a shank D adapted to impart blows of impact to the shank of the drill steel E extending into the chuck F in the front head G in position to be struck by the piston. A front cylinder extension H may be interposed between the cylinder and front head G and the parts may be held together by the usual side bolts, not shown.

In this instance, a rock drill having automatic rotation, is illustrated, and the shank D of the piston is provided with the flutes J engaging the flutes K on the chuck F. A rifle bar L engages the piston and extends through the back cylinder washer O and is formed with the usual ratchet P cooperating with the rotation ratchet ring Q over which is placed the back rotation washer R. A suitable handle S is connected to the rock drill in any convenient manner.

A valve chest T is located at one side of the cylinder and motive fluid, in this instance, is supplied to the machine through the inlet U controlled by the usual throttle valve V having the handle W. Valve bushings X and Y are adapted to be inserted in the valve chest T, and as a convenient construction the bushings X and Y are provided with the chambers a and b, for lightening the construction of the bushings.

The bushings X and Y are so constructed

that the opposed edges *g* and *h* at the meeting faces of the bushings are separated by a space opposite the groove *j* in the valve chest, so that an annular inlet port is formed 5 at this point opposite the inlet *U*. The valve *c* is formed with the end heads *k* and *o* and a central flange *p* of larger diameter than the heads, which flange controls the 10 passage of motive fluid from the inlet *U* to both ends of the cylinder *A*. The flange *p* as shown extends into the annular port between the meeting edges *g* and *h* of the valve bushings, and as the valve reciprocates, the said flange seats upon said opposed 15 edges *g* and *h* which also form stops limiting the movement of the valve. Annular shoulders *p'* are formed on the valve at each side of the flange *p* and these shoulders preferably have sliding contact with the bore of 20 the bushings *X* and *Y*, as the valve reciprocates. In consequence, although the travel of the valve is reduced to a minimum between the opposed edges *g* and *h* of the valve bushings, the actual port openings are controlled 25 by the annular flanges *p'* and the valve openings or spaces allowed for the passage of air between the flanges *p'* and the edges *g* and *h* of the bushings are of less width than the actual valve travel, so that 30 only sufficient air is passed for obtaining maximum efficiency in the operation of the rock drill. The free exhaust *z* in the cylinder *A* controlled by the piston, is preferably 35 designed with relation to the ports controlled by the valve flange *p* to obtain maximum efficiency.

The valve bushings *X* and *Y* are formed with the ports *q* and *r* registering with the 40 passages *s* and *t*, which in this instance cross each other and lead to the opposite ends of the cylinder for supplying motive fluid to the cylinder for the operation of the hammer piston. The bushings *X* and *Y* are also provided with the atmospheric leak ports *u* and *v* preferably connected by grooves or 45 passages *w* and *x* to the ports *w'* and *v'* in the valve bushings, which in turn communicate with the atmosphere through the ports *w'* and *x'* in the valve chest. The atmospheric 50 leak ports *u* and *v* in the valve bushings are so located that they are controlled by the ends *o* and *k* of the valve and alternately vent the space behind the ends of the valve to the atmosphere through the ports 55 *w'* and *x'* which are always in communication with the atmosphere. The ports *u'* and *v'* in the valve bushings leading to atmosphere are also controlled by the ends *o* and *k* of the valve and alternately place the 60 ends of the cylinder in communication with the small atmospheric ports *w'* and *x'* and avoid the building up of compression pressure in the spaces between the central flange *p* of the valve and the ends *o* and *k* of the 65 valve during the operation of the piston.

The valve is preferably hollow with a central web *y* through which small ports *2* and *3* are conveniently located preferably at an angle to the longitudinal axis of the valve, which small ports connect the inlet *U* directly with the spaces *a* and *b* respectively, at the ends of the valve. 70

The valve is positively thrown by live air, the pressure fluid passing to the ends of the valve through the small ports *2* and *3*, and building up pressure at that end of the valve, at which the atmospheric leak port *u* or *v* is closed, the space at the other end of the valve being open to atmosphere, as indicated. The valve is held by the pressure of live motive fluid on one of the faces of the central flange *p*, until such pressure is relieved by opening of the main exhaust *z* by the piston. 75

In the operation of the device, let it be assumed that the piston *B* is moving on its forward stroke, which is about to be completed, as indicated in Figure 1. The valve *c* is as indicated in rearward position, and live motive fluid is passed from the inlet *U* around the valve through the supply passage *s* to the rearward end of the cylinder, driving the piston forward. The pressure of motive fluid on the central flange *p* holds the valve in its rearward position as indicated. Motive fluid passing through the small port *2* in the valve to the space *b* at the rearward end of the valve, tends to build up pressure in the said space and partially balances but does not over-balance the pressure on the flange *p* tending to hold the valve in position. As soon as the piston head *C* uncovers the exhaust port *z* in the cylinder, the pressure on the flange *p* of the valve holding the valve in its rearward position is reduced to atmosphere, and the pressure of live motive fluid in the space *b* will throw the valve forwardly to the position indicated in Figure 2, in readiness to supply air to the forward end of the cylinder for the return of the piston. With the valve in the position indicated in Figure 1, the space between the flange *p* of the valve and the head *k*, is open to atmosphere through the atmospheric port *x'* so that any compression pressure in front of the piston as the piston completes its forward stroke is relieved through the supply passage *t* and the atmospheric port *x'*. 90 95 100 105 110 115

On the return stroke of the piston, as indicated in Figure 2, with the valve in forward position, a similar cycle of events takes place. Pressure fluid is supplied from the inlet *U* around the valve and through the supply passage *t* to the forward end of the cylinder and live motive fluid also passes through the small port *3* in the valve to the space *a* at the forward end of the valve behind the valve head *o* and pressure is built up in said space opposing but not overbal- 120 125 130 135

ancing the pressure of the live air on the flange p tending to hold the valve in forward position. The space between the flange p of the valve and the forward head o , is 5 open to atmosphere through the atmospheric port w' so that compression pressure from the rearward end of the cylinder produced by the piston, is relieved at this point. When the piston overruns the exhaust port z , 10 the pressure holding the valve in forward position is reduced to atmosphere and the live air in the space a at the forward end of the valve throws the valve to rearward position.

15 Since the supply passages s and t from the valve to the ends of the cylinder, cross each other, the machine is always in readiness to start operation. If it be assumed that both the piston and the valve are in their 20 rearward positions, motive fluid will be admitted to the rearward end of the cylinder through the supply passage s to start the piston forward and if both the piston and the valve are in forward position, motive 25 fluid will be supplied to the forward end of the cylinder to drive the piston rearward and in either case, the valve will automatically assume its functions. On the other hand, if for instance the piston should for 30 any reason come to rest in the length of the cylinder, in a position to cover the exhaust port z , the valve would automatically become unbalanced and be thrown to a position to start the piston in operation again, because 35 the continuous building up of live air pressure in a space at one end of the valve and the continual leakage of pressure to atmosphere in the space at the other end of the valve, will cause the valve to be thrown over 40 to a position to supply live air against that face of the piston requisite to move the piston in the direction in which it can most easily move.

I claim:

45 1. In a fluid actuated rock drill, the combination with a cylinder and reciprocating piston of a valve chest, a fluid actuated valve controlling the inlet supply and having a single central flange of larger diameter than the ends of the valve, which flange 50 controls the passage of motive fluid from the inlet to both ends of the cylinder, crossed supply passages connecting the forward and rearward spaces in the valve chest between 55 the central flange and the ends of the valve with the rearward and forward ends respectively of the cylinder, small ports connecting the inlet directly with the spaces at the ends of the valve and a free exhaust 60 port controlled by the piston, and atmospheric leak ports leading from the spaces at the ends of the valve and controlled by the ends of the valve, whereby the valve is thrown in a direction opposite to the direction of travel of the piston by the live mo-

65 tive fluid passing to the ends of the valve through said small ports and building up pressure at one of said ends of the valve until the free exhaust port is opened by the piston and the valve being held by the pressure of live motive fluid on one face of the central flange of larger diameter until the valve is ready to be thrown.

70 2. In a fluid actuated rock drill, the combination with a cylinder and reciprocating piston, of a valve chest, a fluid actuated valve controlling the inlet supply and having a single central flange of larger diameter than the ends of the valve, which flange 75 controls the passage of motive fluid from the inlet to both ends of the cylinder, crossed supply passages connecting the forward and rearward spaces in the valve chest between the central flange and the ends of the valve with the rearward and forward ends respectively of the cylinder, small ports connecting the inlet directly with the spaces at the ends of the valve and a free exhaust port controlled by the piston, auxiliary exhaust 80 ports communicating with the said supply passages and atmospheric leak ports leading from the spaces at the ends of the valve both said auxiliary exhaust ports and leak ports being controlled by the ends of the valve, whereby the valve is thrown in a direction 85 opposite to the direction of travel of the piston by the live motive fluid passing to the ends of the valve through said small ports and building up pressure at one of said ends of the valve until the free exhaust 90 port is opened by the piston and the valve being held by the pressure of live motive fluid on one face of the central flange of larger diameter until the valve is ready to be thrown.

95 3. In a fluid actuated rock drill, the combination with a cylinder and reciprocating piston, of a valve chest, a fluid actuated valve controlling the inlet supply and having end heads and a single central flange of 100 larger diameter than the heads, which flange controls the passage of motive fluid from the inlet to both ends of the cylinder, crossed supply passages connecting the forward and rearward spaces in the valve chest between the central flange and the end heads with the rearward and forward ends respectively of the cylinder, a central annular inlet port in said valve chest into which the central flange of the valve extends and 105 seats and in which the said flange reciprocates, the edges of the said annular port also forming stops for limiting the movement of the valve, small ports connecting the inlet directly with the spaces at the ends of the valve, a free exhaust port controlled by the piston, auxiliary exhaust ports communicating with the said supply passages and atmospheric leak ports leading from the spaces at the ends of the valve, both said 110

auxiliary exhaust ports and leak ports being controlled by the end heads of the valve whereby, the valve is thrown in a direction opposite to the travel of the piston by the live motive fluid passing to the ends of the valve through said small ports and building up pressure at one of the said ends of the valve until the free exhaust port is opened

by the piston and the valve being held by the pressure of live motive fluid on the face 10 of the central flange of larger diameter until the valve is ready to be thrown.

In testimony whereof I have signed this specification.

FRED M. SLATER.
